OTTOMAN CHAIR

Max H. Goldstein, Chicago, Ill.

Application August 29, 1938, Serial No. 227,361

2 Claims. (Cl. 155—171)

This invention relates to ottoman chairs, so called since they include a foot-rest somewhat in the form of an ottoman or low seat-like leg support, whereby the chair with its accompanying foot-rest member may be used for reclining purposes.

The present invention provides an improved chair group of this type, which in small apartments, crowded hotel waiting rooms, beauty parlors or the like, where space is limited, may advantageously be used either as a straight or a reclining chair.

In accordance with my invention my improved device includes means for storing the foot-rest within the frame of the chair when not in use, at which time the foot-rest member serves the useful purpose of providing a front portion of the chair directly beneath the seat portion and desirably flush with the front face of the chair.

The invention will be more fully understood by reference to the following detailed description of the illustrative construction shown in the accompanying drawing forming a part of this specification and in which:

Figure 1 is a perspective view, partially phantom or in section, of a chair group embodying one form of my invention;

Figure 2 is an enlarged longitudinal view of the structure of Figure 1, partially in section;

Figure 3 is a partial plan longitudinal sectional view, somewhat diagrammatic, of one side of the structure of Figure 2.

In the drawing, the chair group 10 as a whole includes the chair proper 11 and the ottoman 12 or foot-rest 12. The chair 11 has the usual frame 13 which provides for a back portion 14, seat portion 15 and legs and arms 16 and 17 respectively.

In this instance, the ottoman proper or foot-rest member 12 is semi-permanently attached to the chair proper 11. For this purpose, the foot-rest is pivoted on the chair frame 13 at the front of the chair and directly below the seat portion 15. As here shown, the pivot pins 18, are inserted laterally inwardly through the side frame portions 19 and are received in appropriate pivot holes in the frame portion 20 of the foot-rest.

Thus when the seat 15 is swung upwardly into dotted line position on its pivot 21, as shown in Figure 2, the foot-rest 12 may be swung on its pivot 18 from its stored position within chair 11 as shown in dotted lines in Figure 2 to its withdrawn position as shown in full lines in Figure 2. At the latter time legs 22 at the free end of the foot-rest being adapted to contact the floor along

with the legs 16, support the foot-rest when in use, in addition to its pivot 18.

In the latter position of the foot-rest, the seat 15 is dropped back on its pivot 21 to full line position in Figure 2 at which time the free or forward end of seat has a surface portion 23 which occupies, when the seat is swung down, a position behind and in this instance above the foot-rest, flush with the front of the chair and together with the foot-rest and the other frame 10 parts providing the front of the chair.

In this latter position of the seat, the free end of the seat is supported independently of the foot-rest on frame blocks 24 fixed on the inner faces of the frame portion 19 at each side of the foot-rest pivot points, these blocks 24 being slightly higher vertically than the vertical height of the foot-rest portion 20 as best shown in Figure 1 so that the free end of the seat rests thereon instead of on the foot-rest. It will be understood that the foot-rest pivot pins 18 pass through these blocks 24 before projecting into the foot-rest frame portion. Also it will thus be seen that the foot-rest is narrower transversely of the chair than the seat part 15 so that when the foot-rest is moved to stored position, in this instance by swinging it back on its pivot to dotted line position in Figure 2, the seat having again been first swung up to dotted line position and then back to normal full line position, the legs 22 of the foot-rest, which are now inverted, are conveniently received within the hollow underside of the seat. In this latter position of the foot-rest, it may be supported by a transverse strap 25, of stout fabric or the like, secured across the lower members of the frame portion 13, as at 25a.

The pivot bolts 21 for the seat advantageously pass through an upright frame portion 26 into the hollow frame member 27 of the seat and may be removed if desired by removing the lock-nuts 28 and the bolts 21, to remove the seat for any purpose. These upright frame portions, 26, which rest at their lower end upon the horizontal members of the frame, desirably provide reinforcing vertical strut supports for the arm frame members 29. This is desirable particularly where such articles of furniture are used in hotels and are subject to frequent usage of the arms as seats.

It will be understood that the entire exposed surfaces of the parts may be covered by the usual fabric or leather upholstery and this upholstery is desirably fastened adjacent the pivot pins 18, of the foot-rest as at 30, by snap buttons or other readily separable fasteners so that the upholstery 55

may be moved aside to withdraw the pivot pins 18 to remove the foot-rest entirely if desired.

It will be understood that the foot-rest in its stored position, by reason of being pivoted on the pivot pins 18 at a point vertically of its surface 5 20 practically exactly in the middle of the vertical height of this surface occupies the same vertical distance at the front of the chair whether the foot-rest is in its stored or withdrawn position and consequently, in its stored position, as shown 10 in Figure 1, the surface 20 of the foot-rest, which is desirably upholstered similarly to the remainder of the foot-rest and to the chair proper itself, provides a portion of the front of the chair 15 flush with the permanent chair front portion 31 and the seat front portion 23.

For example, the cushioned parts of the chair group may contain the usual springs (not shown) and in any provision for moving the foot-rest, the latter is received well within the chair frame and 20 beneath the seat.

Such changes in the chair group of my invention as fall within the scope of the following 25 claims may be made without departing therefrom.

I claim:

1. In an ottoman chair, the combination with 30 an upholstered chair frame, of upholstered seat and foot-rest members carried thereby and movable vertically with respect thereto, said foot-rest member being hinged adjacent its rear face to the front of the chair to be foldable to retracted position beneath or to be extended from the seat when the seat is temporarily elevated above normal position, spaced-apart supports for said seat at 35 the front of said frame, said foot-rest being narrower than the space between the said supports and movable between said supports when the seat is in elevated position, said seat being lowerable

to normal position to rest on said supports and said supports supporting the seat both when the foot-rest is folded beneath the seat and when in extended position after elevation and restoration of the seat to normal position and said rear face 5 portion of the foot-rest forming an exposed finished front portion for the chair beneath said seat when the foot-rest is in retracted position, whereby the foot-rest is visible whether in retracted or extended position while permitting the 10 normal position of the seat to remain the same after elevation for movement of the foot-rest in either direction.

2. In an ottoman chair, the combination with 15 a chair frame, of upholstered seat and foot-rest members carried thereby and movable vertically with respect thereto, said foot-rest member being hinged adjacent its rear face to the front of the chair to be foldable to retracted position beneath or to be extended from the seat when the seat is temporarily elevated above normal position, a support at the front of the chair for said movable seat independent of said foot-rest member, said seat being lowerable to normal position to rest on said support and said support supporting the 20 seat both when the foot-rest is folded beneath the seat and when in extended position after elevation and restoration of the seat to normal position, an exposed upholstered finished front portion for the chair beneath said seat when the 25 foot-rest is in retracted position and forming with said seat and said foot-rest the finished front portions of the chair, said foot-rest being a movable part of said front portions while permitting the normal position of the seat to remain the same 30 after elevation for movement of the foot-rest in either direction.

MAX H. GOLDSTEIN.
